UNITED STATES PATENT OFFICE.

HARVEY F. MITZEL, OF BARBERTON, OHIO.

DESIGN FOR A BATHING-CAP.

SPECIFICATION forming part of Design No. 34,852, dated July 23, 1901.

Application filed May 27, 1901. Serial No. 62,175. Term of patent 7 years.

To all whom it may concern:

Be it known that I, HARVEY F. MITZEL, a citizen of the United States, residing at Barberton, in the county of Summit and State of

5 Ohio, have invented a certain new and original Design for Bathing-Caps, of which the following is a specification, reference being had to the accompanying drawings, forming a part thereof.

10 Figure 1 is a central section in outline of a bathing-cap, showing my new design taken on the line $x-x$ of Fig. 2; Fig. 2, a plan view of the same.

As shown in the drawings, my design consists of a head-band A, integral with and from 15 which the cap extends laterally, forming the

edges B of a flattened ellipsoid, whence the upper part rises in form of a low cone, having concentric undulations C, to a rounded center D at the top.

Having thus described my invention, what I claim as new, and desire to secure by Letters Patent, is—

The design for a bathing-cap, as herein shown and described.

In testimony that I claim the above I hereunto set my hand in the presence of two subscribing witnesses.

HARVEY F. MITZEL.

In presence of—

C. P. HUMPHREY,

C. E. HUMPHREY.
